KILN LINING

Richard W. Burke, Coplay, Pa.

Application September 16, 1932
Serial No. 633,540

1 Claim. (Cl. 222—7)

This invention appertains to new and useful improvements in brick lining for kilns and similar apparatus.

The principal object of this invention is to provide a kiln lining, wherein certain of the lining bricks project to engage and lift the material under treatment as it rotates.

Another important object of the invention is to provide a lining for rotary kilns wherein bricks of the lining project inwardly to catch material and lift the same, instead of permitting the material to remain in the bottom of the kiln as now occurs.

During the course of the following specification and claim, other important objects and advantages of the invention will become apparent to the reader.

In the drawings:—

Figure 1 represents an end elevational view of the lining.

Fig. 2 represents a fragmentary vertical sectional view through the shell of a kiln showing the lining therein.

Fig. 3 represents a perspective view of one of the protruding fire bricks.

Fig. 4 represents a vertical sectional view through one of the projecting fire bricks.

Referring to the drawings wherein like numerals designate like parts, it can be seen that numeral 5 represents the outer shell of a rotary type of kiln. Numeral 6 represents the brick of the usual kiln lining, whereas numeral 7 generally refers to the novel brick making up the present invention.

This brick consists of a rectangular portion A having a flared enlarged head portion 9 along one longitudinal edge thereof. This head tapers inwardly in the manner shown in Fig. 3 so as to engage between adjacent bricks 6 of the kiln lining in the manner substantially shown in Fig. 1.

In the manufacture of this novel brick 7, a plurality of elongated members 10, each provided with a plurality of spurs or anchor members 11 are molded in the brick, having the heads 12 thereof exposed at the inner end of the brick, while the protruding remaining ends of the members 10 are threaded as at 13 and extend through openings in the kiln shell 5. Nuts 14 are engageable on these threaded extensions 13 for firmly securing the bricks to the inner sides of the shell 5 and between the bricks 6 of the lining in the manner substantially shown in Fig. 1.

It can be seen in Fig. 1, that the flared enlarged edge portion of the brick 7 is the portion which fits between the bricks of the lining and

it can also be seen, that with the members 10, which are of metal, disposed entirely through the brick 7, the brick will be reinforced and cannot break off at the lining.

While the foregoing specification sets forth the invention in specific terms, it is to be understood that numerous changes in the specific shape, size and materials may be resorted to without departing from the spirit and scope of the invention as claimed hereinafter.

Having thus described my invention, what I claim as new is:—

In a kiln, a shell, a brick lining for the shell, a plurality of relatively wide bricks, said wide bricks being interposed between the bricks of the lining so as to project inwardly of the kiln beyond the lining bricks, means for securing the wider bricks to the shell, said wide bricks each being provided with a transversely extending reinforcing member protruding beyond the block and its outermost side, said shell being provided with an opening therein, said projecting portion of the reinforcing element being disposed through the opening of the shell, and securing means on the reinforcing element at the outside of the shell.

RICHARD W. BURKE.
